UNITED STATES PATENT OFFICE.

HERBERT C. BLACKMER, OF MELROSE, MASSACHUSETTS.

BINDER.

1,095,547.

Specification of Letters Patent.

Patented May 5, 1914.

Application filed April 24, 1905. Serial No. 257,067.

To all whom it may concern:

Be it known that I, HERBERT C. BLACKMER, of Melrose, in the county of Middlesex and State of Massachusetts, a citizen of the United States, have invented a new and useful Improvement in Binders, of which the following is a full, clear, and exact description, reference being had to the accompanying drawings, forming a part of this

10 specification, in explaining its nature.

My invention relates to an improvement in binders and especially to a binder suitable for books of public record.

The essential object of my invention is 15 to provide a binder so constructed that the bound parts or leaves held by the binder will lie flat without the necessity of holding them back when the binder is opened. This is a serious difficulty in the use of books 20 made up of heavy stiff paper such as that on which public records are kept in that the leaves of the book will not lie flat when the book is opened and especially when the book is opened at some point other than about its 25 center. This is true especially of loose leaf binders or books because the usual binder posts or pins which hold the leaves or bound parts pass transversely through their binding edge which keeps the back of the book 30 from yielding and prevents the leaves from opening out to lie flat.

It is a still further object of my invention to furnish the binder comprising my invention with various new and improved 35 parts, all of which can best be seen and understood by reference to the drawings in which—

Figure 1 shows in perspective a binder or book embodying my invention. Fig. 2 is a 40 cross section of a rear portion of the same. Figs. 3 to 6, inclusive, show in various plans different structural parts of what will hereinafter be described as a modified form of the binder. Fig. 7 shows in cross section 45 the different elements employed in the formation and construction of the modified binder. Fig. 8 shows a vertical section crosswise the back of the modified binder. Fig. 9 shows in side elevation the modified form 50 of binder provided with a back. Fig. 10 is a vertical section crosswise the back of the modified binder showing the same provided with more than two bound sections. Fig. 55 11 shows in cross vertical section the lock used in connection with the hinge forming

a portion of the binder. Fig. 12 shows in vertical section the lock applied to a hinge and especially showing the form of construction of the lock. Fig. 13 shows in plan a mode of making the hinges forming one 60 of the essential elements of the binder. Fig. 14 shows in perspective the members hereinafter referred to forming the telescopic back disconnected from the binder.

Referring to the drawings:—The binder 65 or book D comprising my invention is shown retaining a number of bound sections or leaves B and is constructed as follows:— 70 *d*, *d*¹, respectively, represent its sides or covers, and *d*² its back, which is reinforced by *d*³. Between and joining the respective covers to the back of the book are placed the respective cover boards or binder plates *d*⁴, *d*⁵, each board or plate being joined to the 75 cover by a flexible hinge *d*⁶ and to the back of the book by an auxiliary hinge *d*⁷. The interior of the book, as before described, is made up of the bound sections of leaves B. These sections are separated from one another by hinges E which are composed of 80 two metal plates or leaves *e*, *e*¹, bound by some flexible material or webbing *e*² along one edge, by which the plates may be operated together in the manner of the leaves of a hinge. Joining these hinges together and to the cover boards or plates are independent sets of posts F upon which the sections of leaves B are impaled. I prefer to secure 85 these posts by having one end permanently fixed by threaded connection or otherwise and then completing the connection at the other end of the post by a screw which is provided with a flanged head and which extends through the part to be joined and 90 fastens onto the end of the post, as for example, I have shown these posts permanently joined at one end by screwing into the leaves of the hinges, while the other ends of the posts are secured by screws *f* which either 95 fasten through the cover boards or through the leaves of the hinges. A book thus made can be opened at any point and the leaves lie flat, for as may be seen in Fig. 1, when the book is opened one or both hinges open, 100 depending as the book is opened near the center or nearer one side. With the opening of the hinge or hinges, they, together with the bound parts secured to them, yield 105 or spring forward as with an ordinary bound 110

book, which enables the cover boards or plates, hinged as they are to the back of the book, to open also, so opening the entire back of the binder and enabling the leaves 5 to lie flat. Moreover the leaves will lie flat even when they are bound with the long measurement. Of course, the covers proper hinged to the cover boards or plates may be turned still farther back and lie substantially flat on the surface on which the book 10 is resting. Such opening of the book or binder makes the book open easily and as it is opened to gradually turn or roll over upon its back. Another advantage resides 15 in the fact that if it is desired to renew any one of the bound sections of the book this may be done without disturbing the other sections. Should the covers become worn the interior bound parts may be removed 20 and placed in other covers without disturbing the bound sections or parts, the operation taking but a few moments and requiring no special skill.

While the interposed hinge or hinges are 25 especially adapted to be used in binding sections of leaves bound or locked together as before described, they may, of course, be used with separate or independent loose sheets, which are impaled upon the binder 30 posts or pins in the usual manner.

Reference will now be made to another modified form of binding in which hinges are also used interposed between bound sections of the book and in which, also, provision is made for widening the space for receiving these sections by which the leaves 35 may be built up.

The modified form of binding or book is shown complete in Fig. 9, G representing 40 the book having cover boards or plates g , g^1 , joined to the covers g^2 , g^3 , by the respective joints or flexible connection g^4 , g^5 . Between the respective cover boards are the bound sections of leaves B which are separated by one or more hinges E in the manner before described. I prefer to use but one hinge, but of course more than one may be used as shown in Fig. 10. Each bound section of leaves has separate sets of post 45 supports. The leaves adjacent to the cover boards or plates are impaled upon the posts F projecting from the cover boards or plates on the one side and on the other side supported by another set of posts F^1 projecting from the leaves of the adjacent hinges. In case 50 there are two or more hinges then the section or sections of leaves between the hinges likewise have two separate sets of posts passing through them from opposite sides, the 55 posts being carried by or fixed to the leaves of the hinges. The effect or advantage of the leaves or bound parts being thus impaled upon double sets of posts is that the space between the cover boards and their 60 adjacent hinge or hinges or between sepa-

rate hinges may be widened and the leaves or bound parts still be held in place or at least as long as the sets of opposing posts overlap. Thus provision is made for building up the bound sections or parts. The 70 hinges are adapted to be locked independently together or to the cover boards so locking the sections or leaves between them. For this purpose it is to be noted that there is employed a lock C, one part c of which 75 is carried by the leaf of the hinge and the other part c^1 carried by or secured to the cover board or plate. I prefer to make one part of the lock detachable, so the part c^1 is simply passed through the cover board 80 with its flanged head engaging the same. The part c it is to be noted is preferably made a permanent fixture on the hinge (see Fig. 12). In case two or more hinges are employed then the leaf of one hinge carries 85 one part of the lock and the leaf of the adjacent hinge its complementary part, and one or both of which parts may be detachable, but preferably one part only, as shown. Thus the hinges may not only be adjusted 90 with respect to the cover boards and to each other depending as the sections of leaves or paper are built up between them, but they may also be locked together at different points of their adjustment and the paper 95 locked or bound between them. Moreover it is mechanically obvious that sets of these adjustable locks might also be used as binder posts upon which the bound sections or leaves could be impaled. With respect to 100 the lock also I prefer that it should be made releasable for which purpose I have provided the toothed member c^5 with a lever end c^8 which is so located as to be engaged by a pin or screw c^9 passed down or inserted through the head of the lock, by which means the said member is moved back against the spring pressing against it or away from the member c^4 with which it is in normal engagement, as before described. 105 The lock may then be taken out. In case any bound section or part of the binder is not sufficiently filled with leaves, then a filler H may be employed, which consists of a curved or bow-shaped spring h interposed 110 between the bound section or part and the cover board, as shown in Fig. 8, or between the section and the leaf of any hinge. The bow-shaped spring h is held in place by a plate h^1 to which it is fixed, this plate being held in place by the binder posts or pins and lock C which pass through it. The binder is also shown provided with a detachable and extensible or telescopic back which is especially adapted to be applied separately to 115 each of its sections. The back I comprises the plate members I^1 , I^2 . The member I^1 is composed of the plates i , i^1 bent at right angles to one another, and the plate member I^2 has plates i^2 , i^3 similarly bent, and which 120 125 130

plate i^2 is provided also with clips i^4 at either end for receiving the ends of the plate i when the parts are in conjunction, the plate i being adapted to fit inside and alongside the plate i^2 with its ends contained in the clips at the end of said plate. By this means the plates i , i^2 are adapted to slide by one another so as to be drawn apart and form the extensible or telescopic back proper. The back is applied to the binder by fitting the plates i^1 , i^3 of the respective members over the binder posts outside the bound section or part and between it and the cover board on the one side and the leaf of the adjacent hinge on the other, or if used for backing a bound section, between two adjacent hinges, then the plates i , i^2 are impaled upon the opposite sets of binder posts outside the bound section or part and between it and the leaves of the adjacent hinges. This makes a very simple form of detachable back and one which is also extensible or telescopic depending upon the thickness of the bound parts. Of course, this form of back may be applied to any loose leaf binder made without a back.

By the expression "bound parts" which occurs herein I wish to be understood as meaning either loose leaves held in the binder or sections of leaves, meaning leaves fastened together and afterward placed in the binder.

Having thus fully described my invention, I claim and desire to secure by Letters Patent of the United States:—

1. A binder having binding plates, hinges located between said plates, binder posts or pins interposed between the binding plates and the leaves of hinges adjacent thereto, and binder posts or pins interposed between the leaves of adjacent hinges and upon

which posts or pins the bound parts are adapted to be arranged.

2. A binder having binding plates, hinges located between said plates, binder posts or pins interposed between the binding plates and the leaves of hinges adjacent thereto, binder posts or pins interposed between the leaves of adjacent hinges and upon which posts or pins the bound parts are adapted to be arranged, and adjustable locks connecting each of the binding plates with the leaf of the hinge adjacent to it and connecting also the leaves of adjacent hinges.

3. In a binder, a lock of the character specified having two hollow sections or parts, serrated or toothed members carried by said parts one of which members is fixed, the other pivoted, and which members are adapted to interlock when the parts are united, means for holding said members in a normal engaging position, and a lever projecting from the end of said pivoted member and located in a position whereby it may be engaged by a key passed through the head of said lock for separating its toothed members into a disengaging position.

4. A binder having binding plates, a hinge located between said plates and connected therewith, binder posts or pins interposed between said binding plates and said hinge on which posts or pins the bound parts are adapted to be arranged to form bound sections separated from one another by said hinge, and an extensible back for each one of said bound sections, said back comprising interlocking extensible members connecting with said posts or pins.
